UNITED STATES PATENT OFFICE.

WILLIAM B. GEORGIA, OF WACO, TEXAS.

DESIGN FOR AN EYEGLASS LENS.

Application filed January 26, 1924. Serial No. 8,441. Term of patent 14 years.

To all whom it may concern:

Be it known that I, WILLIAM B. GEORGIA, a citizen of the United States, residing at Waco, in the county of McLennan and State of Texas, have invented a new, original, and ornamental Design for Eyeglass Lenses, of which the following is a specification, reference being had to the accompanying drawing, forming part thereof.

The figure is a plan view of an eyeglass lens showing my new design.

I claim:

The ornamental design for an eyeglass lens as shown.

WILLIAM B. GEORGIA.
